UNITED STATES PATENT OFFICE.

LEE H. PAYNE, OF MILWAUKEE, WISCONSIN.

REFRIGERATING CABINET.

Application filed March 10, 1924. Serial No. 698,030.

To all whom it may concern:

Be it known that I, LEE H. PAYNE, a citizen of the United States, residing at Milwaukee, in the county of Milwaukee and 5 State of Wisconsin, have invented certain new and useful Improvements in Refrigerating Cabinets, of which the following is a specification.

This invention relates to a cabinet for 10 maintaining at a low temperature products, such as ice cream, and the like, and particularly to a refrigerating cabinet in which ice in subdivided form is packed around a container for the goods.

15 It has heretofore been proposed, for the purpose of economizing in the consumption of ice, to limit the vertical dimension of the mass of ice which surrounds the container by excluding the ice from the lower portion 20 of the container-receiving space and using the latter as a brine well, and depending on the salty water which develops from the melting of the ice to keep the lower portion of the container cool; and the object of 25 the present invention is to provide a construction of refrigerating cabinet operating upon this principle, but which will be of simpler construction and more efficient in the cooling capacity of the brine well.

30 Accordingly, the present invention proceeds upon the principle of having the transverse dimensions of the brine well sufficiently near to those of the end of the container, which enters the well, to adapt 35 the container to serve as the ice excluding element, although sufficiently larger than the container to develop an efficient brine circulating space around the inner end of the container; but this brine circulating 40 space is of such restricted capacity that the contained liquid cooling medium, namely, the brine, will circulate therein and be replaced by cooler liquid from the ice pack as fast as the imbalance in temperature develops, and thus not only is the ice excluded from the brine well without the complication of special partitioning means, 45 gratings, and the like, but the brine is prevented from accumulating around the inner 50 end of the container in any such volume as would admit of local circulation and interference with replacement of brine from the melting ice. Means are introduced between the inner end of the container and the walls 55 of the brine well for maintaining distance

of all the walls of the two members, and thus insuring continuity of the brine well entirely around the container; and these spacing means extend beneath the container so as to prevent it resting on the bottom of the well as well as at the sides thereof, as, for instance, by developing the spacing means in the form of straps extending along vertical walls of the container and having deflected ends that enter beneath the container.

In the accompanying drawing—

Figure 1 shows, in vertical section, a refrigerating cabinet embodying the several features of the present invention.

Figure 2 is a horizontal section on the line 2^x—2^x of Figure 1; and

Figure 3 is a detail view, in perspective, showing one of the straps for spacing the container in the well.

1 represents a refrigerating cabinet constructed with inner wall 2, outer wall 3, and heat insulating material 4 between said walls, and 5 represents a container for goods to be kept cool by means of a packing 6 of ice surrounding the container. According to the present invention, the interior space of the cabinet 1, in which the container 5 is received, is subdivided into an ice chamber 7, which, while completely surrounding the container 5, is nevertheless terminated short of the lower end of the container, and said lower end is accommodated in a brine well 8. While that portion of the inner wall 2 of the cabinet 1 which develops the ice chamber 7 is spaced a considerable distance from the container 5 in order to admit the substantial mass of ice, the relative transverse dimensions of the brine well 8 and the lower end of the container 5 are such as to leave a space between these members that is too small to admit of pieces of ice although sufficient to permit brine, which naturally settles from the ice pack, to substantially surround the 100 container and insure cooling of the lower end thereof.

In order to uniformly space the lower end of the container from the walls of the brine well 8, straps 9 are symmetrically distributed in said space, preferably at the corners, when the opposed walls of the container and well constitute the sides of a polygon, and these straps have their ends 10 deflected beneath the bottom of the container 110

5 so that they keep the latter from resting upon the bottom of the well 8, and excluding brine from the bottom space.

I claim:

- 5 1. In a refrigerating cabinet, an ice-receiving chamber, a brine well at the inner end of and of less transverse dimension than said chamber, and a container extending from the chamber into said well and of a 10 dimension which leaves between the container and the walls of the well a space that will not admit of ice but which is sufficient to permit brine from the ice chamber to circulate therethrough; means being provided 15 in the brine well for spacing the walls of the container and brine well at intervals, and maintaining the brine space around the container.

2. In a refrigerating cabinet, an ice-receiving chamber, a brine well at the inner end of and of less transverse dimension than said chamber, and a container extending from the chamber into said well and of a dimension which leaves between the container and 20 the walls of the well a space that will not admit of ice but which is sufficient to permit brine from the ice chamber to circulate therethrough; means being provided in the brine well for spacing the walls of the container and brine well at intervals, and maintaining the brine space around the container; said means being located beneath the end as well as at the sides of the container.

3. In a refrigerating cabinet, an ice-receiving chamber, a brine well at the inner end of and of less transverse dimension than said chamber, and a container extending from the chamber into said well and of a dimension which leaves between the container and the walls of the well a space that will not admit of ice but which is sufficient to permit brine from the ice chamber to circulate therethrough; means being provided 35 to permit brine from the ice chamber to circulate therethrough; means being provided 40

for spacing the walls of the container and brine well at intervals, and maintaining the 45 brine space around the container; said means comprising straps distributed at intervals around the container.

4. In a refrigerating cabinet, an ice-receiving chamber, a brine well at the inner 50 end of and of less transverse dimension than said chamber, and a container extending from the chamber into said well and of a dimension which leaves between the container and the walls of the well a space that will not admit of ice but which is sufficient to permit brine from the ice chamber to circulate therethrough; means being provided 55 for spacing the walls of the container and brine well at intervals, and maintaining the 60 brine space around the container; said means comprising straps distributed at intervals around the container, and having their ends deflected beneath the container and supporting the container above the bottom of the brine well.

5. In a refrigerating cabinet, an ice-receiving chamber, a brine well at the inner end of and of less transverse dimension than said chamber, and a container extending 70 from the chamber into said well and of a dimension which leaves between the container and the walls of the well a space that will not admit of ice but which is sufficient to permit brine from the ice chamber to circulate therethrough; means being provided 75 within the brine well for spacing the walls of the container and brine well at intervals, and maintaining the brine space around the container; the brine well being of polygonal 80 transverse section, and the spacing means being located at the corners of the polygon.

Signed at Milwaukee, Wisconsin, this 4th day of March, 1924.

LEE H. PAYNE.
